UNITED STATES PATENT OFFICE.

ERNST LINDNER, OF NEW YORK, N. Y.

DESIGN FOR A GAS-FIXTURE.

SPECIFICATION forming part of Design No. 26,560, dated January 26, 1897.

Application filed January 6, 1896. Serial No. 574,549. Term of patent 7 years.

To all whom it may concern:

Be it known that I, ERNST LINDNER, a citizen of the United States, residing at New York, in the county and State of New York, have invented and produced a new and original Design for Cigar-Lighter By-Pass Cocks, 5 of which the following is a specification, reference being had to the accompanying drawings, forming a part thereof.

10 In the annexed drawings, in which like features are indicated by like letters of reference in both views, Figure 1 is a front elevation, and Fig. 2 a side elevation, of a cigar-lighter gas-cock embodying my design, these two 15 views being deemed necessary to fully illustrate my design.

The invention relates to a new and original design for a gas-fixture of the character used as cigar-lighter gas-cocks; and the invention 20 consists in the configuration or shape of the fixture substantially as shown in the drawings.

The design for the fixture consists of the globe-shaped body A, a key B, which projects

from the center of one side of body A, and 25 terminates in a neck c, supporting a globe-shaped end b, which is smaller than globe A. The axis of globe b, which, extended, passes through the axis of key B, also passes through the center of globe A. Hence when seen as 30 in Fig. 1 the small globe b appears to stand centrally against globe A. Globe b has lateral projections d extending therefrom on opposite sides and terminating in rounded ends.

The distinguishing features of the design 35 are the large and small globe-shaped parts A b side by side with intermediate neck C, globe b having extensions d.

I claim—

The design for a gas-fixture substantially 40 as herein shown and described.

Signed at New York, N. Y., the 31st day of August, 1895.

ERNST LINDNER.
